tion of Illinois

Application May 6, 1943, Serial No. 485,872

12 Claims. (Cl. 1—15)

1 This invention relates to stitching machines and more particularly to the general type of machine as disclosed in applicants' copending application, Serial No. 472,316, filed January 14, 1943.

It is the principal object of this invention to provide a stitching machine adapted to form flat, tight-fitting stitches in hard material such as sheets of metal or the like with the stitches extending in a direction transverse to the line of feed of the material.

It is a further object to provide a machine of this character having a clincher mechanism carried by an arm on or over which the work is received, the clincher mechanism being located closely adjacent the side and outer end of the arm so that a minimum of clearance space is required making it possible to form and clinch the stitches close to a corner of the work, for example the inside corner of a box-like structure.

It is a still further object of the invention to provide such a stitching machine in which the stitches are formed in a direction transverse to the line of feed of the work material and having a power actuated clincher plunger for effecting the flat clinching of the legs of the stitch with the clincher mechanism arranged to effect the clinching of the legs of the stitch in such relative positioning.

It is also an object to provide a clincher mechanism for such a stitching machine which may be easily adjusted and maintained accurately in a predetermined adjusted position and in which the parts of the clincher mechanism subject to heavy wear may be readily removed and replaced.

Other objects and advantages will be apparent from the following description, the accompanying drawings and the appended claims.

Referring to the drawings which disclose a preferred embodiment of the invention,

Fig. 1 is a perspective view with certain parts being broken away showing a stitching machine constructed in accordance with the present invention;

Fig. 2 is a view partially in section and partially in side elevation showing the clincher mechanism at the outer end of the arm on an enlarged scale;

Fig. 3 is a view lengthwise of the arm looking down upon the top of the arm from a position to one side thereof partially in plan and partially in horizontal section along the line 3—3 of Fig. 2 showing the construction of the clincher mechanism and also showing in broken form the

2 drive for actuating the clincher plunger and the support for the arm;

Fig. 4 is an end elevational view of the outer end of the clincher arm and clincher mechanism looking inwardly in the direction of the pedestal;

Fig. 5 is a plan view on an enlarged scale looking down upon the clincher mechanism in the same relative position as Fig. 3; and

Fig. 6 is a detail sectional view of the construction providing for the removal and replacement of the clincher plunger.

Referring to the drawings which disclose a preferred embodiment of the invention, the machine is shown as having a main frame including a base portion 10, an upwardly projecting pedestal 11, and an overhanging head 12. The drive motor 14 is mounted in the rear portion of the head and has a suitable driving connection to the main shaft 15. Shaft 15 extends through the head to the front part thereof where the mechanism for forming and driving the stitches is located, the position thereof being indicated by reference numeral 16. A coil of wire 17 is mounted in a convenient location on the head and the wire feeds into the stitch forming mechanism in the usual way where it is formed into an inverted U-shaped stitch, the two legs of the stitch being driven downwardly into and through the work material received beneath the head.

The construction of the angle head stitcher is known in the art, and it is not necessary to describe the details thereof, beyond noting that the head is so constructed and arranged that it provides for forming the stitch in such a way that it stands generally transverse with respect to the direction of feed of work material under the stitching head and parallel with the longitudinal dimension of the arm, and is preferably displaced with respect to the vertical central plane of the pedestal so that the stitch is actually formed and driven in this plane, the drive mechanism being suitably offset to provide for such relationship.

An arm 20 is provided on which the work is received, such arm also carrying the clincher mechanism which provides for clinching the two legs of the stitch after they have been forced through the work material and flattening the legs against the lower face of the material. Both the arm and the frame are of sturdy construction being preferably formed as relatively heavy castings to provide a rigid structure having a minimum of deflection under the loads encountered in use. Arm 20 is adjustably carried

on the pedestal, and is so mounted as to have vertical adjustment thereon to accommodate work material of different thickness, and also is arranged to have lateral adjustment to properly center the clincher mechanism with respect to the location at which the stitch is formed.

The clincher mechanism is constructed and arranged to receive and clinch the legs of the stitch in substantially the plane of the longitudinal dimension of the arm, and is likewise offset, being located relatively close to one side of the arm and adjacent the outer end thereof, so that the stitch itself remains within substantially the central vertical plane of the entire machine. In this way the stitch may be located close to the edge of the work material and a minimum clearance around the stitch is required.

To provide for obtaining such positioning and adjustment of the clincher arm and mechanism, the face of pedestal 11 is formed with the spaced ways 22 and with vertical bearing surfaces 23 against which corresponding surfaces of the arm are adapted to bear. The arm is formed with rearwardly extending projections 24 within which there are mounted studs 25 having engagement with wedge shaped gibs 26 adapted to bear against the ways 22, respectively, end plate 27 preventing lateral displacement of the gibs. By suitably adjusting the studs 25, it will be evident that the entire arm can be shifted laterally from one side to the other while still maintaining its firm support upon the ways, and when so adjusted and with the wedges again tightened it will be securely retained in such adjusted position. Preferably three such sets of bolts 25 are located in vertically spaced relation on arm 20 to provide maximum security and accuracy of positioning. It will be clear also that with the bolts 25 spaced vertically as shown, it is possible to loosen the uppermost while tightening the lowermost, and vice versa, and in this way rock the arm about its longitudinal axis as may be necessary to maintain it level and parallel with the forming mechanism.

In order to secure vertical adjustment in the location of the arm while at all times maintaining the arm in desired level horizontal relation, the arm is provided with enlarged apertures 39 adjacent its inner end which are adapted to receive locking bolts 32 threadedly received in the face of the pedestal 11. The enlarged apertures permit adjustment both vertically and laterally and the bolts at the top of the arm take the load in tension and support the arm firmly.

To effect vertical adjustment of the arm, a pair of downwardly projecting lugs 34 is provided on the lower face of the arm 20 and a connecting pin 35 having a threaded part 36 is secured thereto. Nuts 37 are threadedly received on pin 36 and are located on opposite sides of an abutment 38 secured to the face of the pedestal. Thus it will be apparent that having first loosened bolts 32, the entire arm may be raised or lowered upon the pedestal to adjust the position of the arm to a different level by suitably adjusting either the upper or the lower of the nuts 37. The nuts 37 and bolts 32 are then again tightened to securely lock and retain the arm in adjusted position. Since it is desirable to have as little movement of the arm as possible in the course of the stitching operation, the gibs 26 are preferably set up to such an extent that they tightly hold the arm and preferably with sufficient frictional force to prevent downward

movement thereof under the action of gravity. The arm can however be readily actuated either up or down by the means described above, and thus adjustment is simplified while at the same time maintaining firm and secure support for the arm throughout its operation. Suitable indicating and index means may be provided as desired to facilitate the setting of the arm.

For the purpose of actuating the clincher plunger, the drive shaft 15 is provided with a cam 40 which actuates a connecting rod 41, such rod in turn operating a bell crank lever 42 pivotally supported at 43 on frame 11. The opposite end of the bell crank engages a push rod 44 which is mounted for movement in a substantially longitudinal direction in the frame, and projects parallel with the arm 20 and into a position adjacent the inner end and below the working surface thereof. Arm 20 carries a push rod 45 supported in extensions formed in the lower side of the arm and in a protected position beneath the working surface thereof, push rod 45 being parallel to and having abutting engagement with the end of rod 44. In order to provide for maintaining the operative relationship established between the two rods 44 and 45 throughout the extent of the vertical and lateral adjustment of the arm 20, one or the other of these rods is provided with an extended bearing surface so that proper engaging relation is maintained notwithstanding relative travel of the arm and its rod 45. In the form shown, rod 44 is sufficiently large in diameter to have an end face 44a so that it will have proper driving relation with rod 45 in all relative positions thereof. Rod 45 is retained in one side of offset arm 20 by means of bearing members 46, and is normally urged into contact with rod 44, in a direction to retract the clincher plunger, by means of spring 47.

Suitable means are likewise provided for adjustment in the extent of movement of the clincher plunger and in the upper elevation which it reaches, to determine the force with which the plunger bears against the legs of the stitch, and the extent to which it is flattened against the work. Such adjustment can be incorporated at any suitable point in the clincher actuating mechanism and the adjustment may be made accessible either from the rear of the pedestal or from a protected position beneath the arm. It will be obvious that in this way the effective length of the connecting rod 45 is altered thereby changing the range of travel of the plunger relative to the arm and the dies supported thereon.

The clincher mechanism is carried at the outer end of arm 20 and is indicated generally by reference numeral 50. The end of the arm is recessed to receive a frame member 51 of generally inverted U-shape which fits within the recess and is supported with its two legs extending downward and resting upon a part 52 which is integral with arm 20. Bolts 53 removably secure the frame in position upon the arm. Part 52 thus serves to take the downward thrust upon the clincher mechanism, and the reaction tending to move the clincher mechanism outwardly of the arm is taken by means of bar 54 bolted to the end of arm 20 by means of bolts 55 and having a part 56 overlapping one leg of the frame and thus resisting the tendency to outward movement thereof.

The frame also embodies an upwardly extending web portion 60 to opposite sides of which are

releasably secured clamp members 61 and 62 by means of bolts 63. The clamp members project forwardly beyond the central web and are formed with recessed portions 64 at their overhanging ends to provide for receiving and securely holding a pair of die members 66 and 67. These die members are correspondingly recessed to fit accurately within the ends of the clamps, so that when tightened, the clamps will hold the dies in assembled position as shown in Fig. 5, forming a vertically extending guideway for receiving a clincher plunger, an aperture 68 being formed through the base of the frame 51 of sufficient size to allow such passage of the clincher plunger. Since the dies are subjected to heavy wear in supporting the work material and receiving the ends of the stitch as they are forced through the work material and into the outer ends of the dies which are suitably shaped as shown to receive the stitch, it is desirable to provide for their ready removal and replacement, this being effected in the present construction by means of the releasable clamping members 61, 62. It is not necessary to completely remove the clamps when it is desired to release the dies, as the mere loosening of bolts 63 and the clamps, will permit the dies to be withdrawn and replaced. Preferably the recesses 64 and the dies 66, 67 are made symmetrical so that after being used on one side, they may be withdrawn and inverted to be assembled in reversed relation with their lower sides uppermost, thereby providing additional wear from the same elements.

A shaft 75 is mounted between the legs of the frame 51 and serves as a support for rotatably mounting a bell crank lever 76. This lever has a notched out portion 77 for engagement with a drive pin 78 carried by the forward end of the push rod 45, thereby providing for the power actuation of the lever.

The lever 76 is of less thickness than the space between the legs of the frame member, and is so mounted on shaft 75 as to provide for bodily movement axially of the shaft. The lever carries a projecting portion or pin 80 which has driving engagement in an aperture 81 formed in the clincher plunger 82, the clincher plunger being suitably shaped to engage at its end the legs of the stitch and to flatten them down tightly against the lower surface of the work. Preferably the clincher plunger is constructed as described in said copending application, Serial No. 472,316, being symmetrical so that it can be inverted and additional wear thus obtained.

In its normal driving relation, lever 76 is moved bodily along shaft 75 toward the clincher plunger 82 and pin 80 is normally engaged in driving relationship therewith. In order to keep the lever in driving engagement, a pivoted latch member 84, adjustably supported on bolt 85 carried by one of the legs of the frame 51 is arranged to engage the side face of the lever, and is of sufficient thickness to keep the lever normally in engaging relationship with the plunger. The latch has a manual operating portion 86 providing for the swinging of the latch to a withdrawn position where the lever is permitted to move axially of shaft 75 to disengage the drive pin from the clincher plunger. This disengagement may be facilitated by the manual shifting of the lever to a release position when the latch has been withdrawn.

When so withdrawn, the clincher plunger is free to be removed downwardly through the dies, and to be reversed or replaced as desired. The latch is formed with a beveled face 88 and the

bell crank with a correspondingly beveled face 89 so that upon return movement of the latch, the lever is cammed back to the engaging position where it is kept throughout the normal operation.

- 5 This construction, therefore, facilitates the removal and replacement of all parts of the clincher mechanism which are subject to heavy wear in use, particularly the dies and the clincher plunger itself. Furthermore the arm provides a firm and rigid support for the clincher mechanism with the same being arranged to receive the stitch extending generally parallel with the longitudinal dimension of the arm, and located substantially in the vertical central plane of the entire machine.
- 10 15 Further the adjustment of the arm, either vertically or laterally, does not affect the adjustment of the clincher mechanism, and does not require any change or disconnection in the drive mechanism therefor. Likewise the clincher plunger may be adjusted to drive against the legs of the stitch with a predetermined force and having secured the proper adjustment of the clincher plunger operation, the arm 20 may be then reset for work of different thickness, and
- 20 25 notwithstanding the raising or lowering of the arm, it is not necessary to readjust the operation of the clincher plunger. Since the two adjustments are independent the setting of the plunger is retained and it provides for making the same type of clinch on the new work as before, this being a distinct advantage where work of different thicknesses is being handled. The entire mechanism is highly satisfactory and compact in form, and provides for the location of the
- 30 35 stitches in the direction described and almost immediately adjacent the corner of the arm requiring a minimum of clearance with respect thereto.

40 While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a stitching machine of the character described having a base, a pedestal, an arm, means for supporting said arm from said pedestal, and a stitcher head also supported from said pedestal and arranged to form and drive a stitch toward said arm with the stitch generally parallel with the longitudinal dimension of said arm, the combination of clincher mechanism carried by said arm for effecting the clinching of the legs of the stitch, means for securing said clincher mechanism to said arm in position closely adjacent one side and at the outer end of said arm providing for receiving work material thereon with a lesser clearance from one side thereof than from the other, and means carried on said pedestal and forming a driving connection for effecting the actuation of said clincher mechanism.
- 55 60 65

2. A stitching machine of the character described the combination of a base, a pedestal, an arm having a supporting base, means for supporting the base of said arm centrally upon said pedestal and providing for vertical and lateral adjustment thereof, the outer portion of said arm being laterally offset from the center line of said pedestal, a stitcher head carried by said pedestal and arranged to form and drive the stitches with the direction of the stitch generally parallel with the longitudinal dimension of said
- 70 75

arm and substantially centrally with respect to said pedestal, and clincher mechanism carried at the outer end of said arm and adjacent one side thereof to locate said clincher mechanism in cooperative relation with said stitcher head.

3. In a stitching machine of the character described having a base, a pedestal, an arm, means for supporting said arm from said pedestal, and a stitcher head also supported from said pedestal and arranged to form and drive a stitch toward said arm with the stitch generally parallel with the longitudinal dimension of said arm, the combination of, clincher mechanism carried by said arm for effecting the clinching of the legs of the stitch including means forming dies for supporting the work material and receiving the ends of the stitch, said die means being spaced from the outer end of said arm by only the dimensions of the die itself, and clamp means supported on the outer end of said arm and along one side thereof for releasably retaining said dies in operative position at said one side and immediately adjacent the outer end of said arm providing for receiving the work thereon with a lesser clearance from one side thereof than from the other.

4. In a stitching machine of the character described having a base and a pedestal, an arm, means for supporting said arm from said pedestal, and a stitcher head also supported from said pedestal and arranged to form and drive a stitch toward said arm, the combination of clincher mechanism carried by said arm for effecting the clinching of the legs of the stitch including means forming dies for receiving the ends of the stitch and forming a guide, a clincher plunger movable in said guide to clinch the ends of said stitch, clamp means supported on the outer end of said arm and along a side thereof for releasably retaining said dies in operative position at the side of said arm, fastening means located inwardly of said die means for securing said clamp means upon said arm, said clamp means extending outwardly beyond said fastening means to receive said die means in position immediately adjacent the outer corner of said arm providing for receiving the work thereon with a lesser clearance from one side thereof than from the other, and drive means carried by said arm and having a part extending closely adjacent the outer end of said arm for engaging said plunger to drive the same in said guide.

5. A stitching machine of the character described the combination of a base, a pedestal, an arm having an inner supporting part, means for receiving said inner part of said arm centrally upon said pedestal in supporting relation thereon and providing for vertical and lateral adjustment thereof, said arm having an outwardly extending offset part bringing one side thereof substantially in line with the vertical central plane of said pedestal, a stitcher head carried by said pedestal and arranged to form and drive the stitches with the direction of the stitch generally parallel with the longitudinal dimension of said arm and in said central vertical plane, and clincher mechanism carried at the outer end of said arm and adjacent said offset side thereof to locate said stitcher mechanism in cooperative relation with said stitcher head.

6. A clincher mechanism for use with a wire stitching machine of the character described having a supporting arm comprising a frame member, means for detachably securing said frame member upon said arm, a pair of die members, means for releasably securing said die mem-

bers in assembled relation upon said frame forming a guide for a clincher plunger, an actuating member for said clincher plunger having a portion projecting therefrom, means mounting said actuating member upon said frame member for bodily movement toward and away from said clincher plunger to provide for engagement and disengagement of said projecting portion thereof with said clincher plunger, and means for normally retaining said actuating member in operative position with its said projecting portion in engagement with said plunger and adapted to be moved to an inoperative position to provide for movement of said actuating member to disengage its said projecting portion from said plunger to a release position.

7. A clincher mechanism for use with a wire stitching machine of the character described having a supporting arm comprising a frame member, means for detachably securing said frame member upon said arm, a pair of clincher die members, means for releasably securing said die members in assembled relation upon said frame forming a guide for a clincher plunger, an actuating member for said clincher plunger having a portion projecting therefrom, means mounting said actuating member for bodily movement to provide for engagement and disengagement of said projecting portion with said clincher plunger, and means for normally retaining said actuating means in engaged position with said plunger, said retaining means providing upon displacement thereof from said normal position for movement of said actuating member to a release position, said retaining means and said actuating member having cooperating parts adapted upon movement of said retaining means to said normal position to effect movement of said actuating member to its said engaged position.

8. A stitching machine of the character described comprising a base, a pedestal, a stitcher head, an arm having a base supported centrally from said pedestal and having an outer portion laterally offset with respect to said base and extending in operative relation with respect to said stitcher head, means for adjustably securing said arm upon said pedestal providing for vertical, lateral and angular adjustment about the longitudinal axis of the arm, said stitcher mechanism being arranged to form and drive a stitch in a direction substantially parallel with the longitudinal dimension of said arm and substantially centrally of said pedestal, a clincher mechanism carried by said arm and including a movable clincher plunger, means supporting said clincher mechanism in said arm with said plunger also substantially parallel with the longitudinal dimension of said arm and substantially centrally of said pedestal, and drive means in said arm for effecting driving actuation of said plunger.

9. A stitching machine of the character described comprising a base, a pedestal, a stitcher head, an arm supported from said pedestal in operative relation with respect to said stitcher head, means for adjustably securing said arm upon said pedestal providing for vertical and lateral adjustment in the relation thereof, said stitcher mechanism being arranged to form and drive a stitch in a direction substantially parallel with the longitudinal dimension of said arm, a clincher mechanism carried by said arm and including a movable clincher plunger, means supporting said clincher mechanism in said arm with said plunger also substantially parallel with the

longitudinal dimension of said arm, drive means in said arm for effecting driving actuation of said plunger, and means providing a maintained driving connection from said pedestal to said drive mechanism throughout the normal range of adjustment of said arm.

10. Clincher mechanism for use with a wire stitching machine of the character described having a supporting arm comprising a generally U-shaped frame member, means for detachably securing said frame member upon said arm, a pair of clincher dies, means for releasably securing said dies in assembled relation upon said frame forming a guide, a clincher plunger movable in said dies, a shaft carried by the arms of said U-shaped member, a bell crank rotatably supported by said shaft and movable axially with respect thereto, said bell crank having a projecting portion adapted to engage said plunger in an operative driving position thereof and to be disengaged from said plunger upon axial movement to an inoperative position, and a latch member carried by said frame movable to a position to maintain said bell crank in engaged relation with said plunger and movable to a release position providing for axial movement of said lever to disengage said plunger.

11. Clincher mechanism for use with a wire stitching machine of the character described having a supporting arm comprising a frame member, means for detachably securing said frame member adjacent the outer end of said arm, a pair of recessed clamp members, fastening means located inwardly of the outer end of said

arm for releasably securing said clamp members upon said frame, a pair of dies correspondingly recessed and adapted to be securely held by said clamp members in assembled position forming a guide for a clincher plunger, and a clincher plunger movable within said dies, said dies being removable and replaceable upon the loosening of said clamp members.

12. In a stitching machine of the character described having a base, a pedestal, and a stitcher head carried by said pedestal and arranged to form and drive the stitches with the direction of the stitch generally parallel with the longitudinal direction of said arm and substantially centrally with respect to said pedestal, the combination of an arm having a supporting base, means for supporting the base of said arm centrally upon the said pedestal and providing for vertical and lateral adjustment thereof, the outer portion of said arm being laterally offset from the center line of said pedestal, clincher mechanism carried by said arm for effecting the clinching of the legs of the stitch including means forming dies for supporting the work material and receiving the ends of the stitch, and clamp means supported on the outer end of and at the side of said arm for releasably retaining said dies in operative position at one side and adjacent the outer end of said arm providing for receiving the work thereon with a lesser clearance from one side thereof than from the other.

WILLIAM R. SPILLER,
ROBERT J. NIEDERHAUSER.
